(57) **CLAIM**

The ornamental design for an outboard motor housing, as shown and described.

DESCRIPTION

FIG. 1 is a top front left perspective view of the outboard motor housing.

FIG. 2 is a front view of the outboard motor housing.

FIG. 3 is a back view of the outboard motor housing.

FIG. 4 is a right view of the outboard motor housing.

FIG. 5 is a left view of the outboard motor housing.

FIG. 6 is a top view of the outboard motor housing; and,

FIG. 7 is a bottom view of the outboard motor housing.

The dashed lines in the figures depict portions of the outboard motor housing that form no part of the claimed design. The dot-dash lines in the figures depict portions of the outboard motor housing that are outside the boundaries of the claimed design and form no part thereof.
